UNITED STATES PATENT OFFICE

102,346

DESIGN FOR A SANDAL OR SIMILAR ARTICLE

Jacob Stein, New York, N. Y.

Application November 3, 1936, Serial No. 65,664

Term of patent 14 years

To all whom it may concern:

Be it known that I, Jacob Stein, a citizen of the United States, residing in the city, county, and State of New York, have invented a new, original, and ornamental Design for a Sandal or Similar Article, of which the following is a specification, reference being had to the accompanying drawing forming a part thereof.

The figure is a perspective view of a sandal or similar article showing my new design. Both sides of the upper are identical and the ankle closure is of uniform appearance, save for the buckle at one side thereof.

The sandal shows a backless upper made of mesh fabric and having an ankle closure. Said ankle closure has separate ends, which are connected by the buckle. The essential feature of the design is the combination of a backless upper and the ankle closure.

I claim:

The ornamental design for a sandal or similar article, substantially as shown and described.

JACOB STEIN.
